UNITED STATES PATENT OFFICE.

JOHN WILLIAM HENSON, OF NEW YORK, N. Y.

CURTAIN-LOOPER.

No. 820,786.

Specification of Letters Patent.

Patented May 15, 1906.

Application filed January 6, 1906. Serial No. 294,881.

To all whom it may concern:

Be it known that I, JOHN WILLIAM HENSON, a subject of the King of Great Britain, and a resident of the city of New York, borough of Brooklyn, in the county of Kings and State of New York, have invented a new and Improved Curtain-Looper, of which the following is a full, clear, and exact description.

This invention relates to improvements in means for looping or draping curtains, particularly lace curtains, the object being to provide in connection with a curtain a draw-string so arranged that the body portion of the curtain may be looped or folded from the border outward, thus leaving the inner edge of the border in full view from the top to the bottom.

I will describe a curtain-looper embodying my invention and then point out the novel features in the appended claim.

Reference is to be had to the accompanying drawing, forming a part of this specification, in which similar characters of reference indicate corresponding parts in the figure representing the invention applied.

The figure of the drawing shows a pair of curtains with looping devices embodying my invention, one of the curtains being looped.

Referring to the drawing, 1 designates a pair of curtains having a border 2 at their in-

ner edges. Rove through the curtain material from the inner edge of the border outward and at an upward angle on each curtain is a double draw-string 3. Preferably this draw-string will be arranged in a reinforcing portion 4, and at the outer end the draw-string is provided with a loop 5 for engaging with the usual fixture or hook attached to a window-casing.

In operation by drawing upon the inner end of the string the body of each or either curtain will be folded or looped, as indicated at the right-hand side of the drawing, and the inner ends of the draw-string are then to be tied together, leaving the border in view from top to bottom.

Having thus described my invention, I claim as new and desire to secure by Letters Patent—

The combination, with a curtain having a border at its inner edge, of a reinforce extended transversely from the border, and a draw-string in said reinforce.

In testimony whereof I have signed my name to this specification in the presence of two subscribing witnesses.

JOHN WILLIAM HENSON.
